CLAIM

The ornamental design for a handspray faucet set, as shown and described.

DESCRIPTION

FIG. 1 is a perspective view of a handspray faucet set, showing our new design;

FIG. 2 is a rear elevation view thereof;

FIG. 3 is a front elevational view thereof;

FIG. 4 is a top plan view thereof;

FIG. 5 is a bottom view thereof; and,

FIG. 6 is a right side elevational view thereof, the left side being a mirror image thereof.
